UNITED STATES PATENT OFFICE

2,165,408

TABULATING MACHINE

Edward Rowland Myers, Ottawa, Ontario, Canada, assignor to Remington Rand Inc., Buffalo, N. Y., a corporation of Delaware

Application December 12, 1935, Serial No. 54,010

10 Claims. (Cl. 235—61.7)

This invention relates to tabulating machines, that is to say, to statistical and accounting machines which operate on previously perforated cards, and either print the data indicated on the cards, or accumulate such data, or both. In the 5 illustrative example of the invention disclosed in the drawings and described hereinafter, said invention is adapted to operate with the mechanism located in the base section of the tabulating machine. This base section is fully disclosed and described in the patent to W. W. Lasker, 10 2,044,119 for improvements in Tabulating machines.

This device is adapted for use in "billing tabulators". A group of cards containing the debtor's name, address and items of the bill, each on a separate card are run through the machine. Each of the cards contains interrelated data such as the account number. Machines of this 15 character contain a group control mechanism which is adapted to cause the taking of a total whenever the interrelated data or designation changes. It is proposed to control the invention by said control mechanism in such a manner that, if the 20 designation changes, while the second card, i. e. the address card is being sensed, the machine will be stopped. However, after the address card has passed out of the sensing chamber, any 25 change-of-designation will cause the machine to take a total in the normal manner without being stopped. It is obvious that a device of this character will remove the possibility of wrongly addressing a bill.

The principal object of the invention is to provide an improvement in the operating mechanism of the tabulator which will insure that the machine will be stopped if cards containing interrelated data do not follow one another in the correct sequence.

40 A further object is to provide a mechanism which will be efficient and accurate to prevent the incorrect operation of the tabulating machine.

A more clear conception of the construction 45 operation and further objects of the invention may be had from the following specification taken in conjunction with the accompanying drawings, in which:

Fig. 1 discloses a tabulating machine with portions of covers cut away to show the invention.

Fig. 2 is an enlarged detail view of the principal parts of the invention.

Fig. 3 is a plan view of Fig. 2.

Fig. 4 is a simplified disclosure of the parts

which control the starting and stopping of the tabulator.

Fig. 5 is a detail view of the control plate in its extreme operated position.

Fig. 6 is a cross section through 6—6 of Fig. 5 showing the feed pawl.

Fig. 7 is a schematic diagram of the electric circuit for use with the invention.

Fig. 8 is a detail view partially in cross section of the sensing and reading retaining pins and 10 their associated mechanisms.

To more clearly locate and define the operation of this device, a short description of the normal operation of the machine will be given. The information is contained in perforated 15 cards, one card for each of the items, which are sensed by sensing pins in the mid section 3 (Fig. 1) of the machine. These pins set stops to limit the travel of printing sectors and accumulator wheels. The accumulator wheels store and add 20 items until such time as a change of designation occurs when the total mechanism is operated by a group automatic control mechanism. The whole device is driven by a mechanism contained in the base which is well known in the art, and 25 disclosed and described in the patent to Lasker, mentioned above. Therefore, no further description or disclosure is believed necessary.

In Fig. 1 is shown a side view of a tabulator with portions of the case broken away to disclose 30 those parts of the machine which are involved in the direct operation of the new device. The base section 2 is broken away to show the principal parts used for manually and automatically stopping the machine. In the mid section 35 3 is located the so-called change of designation or groups control mechanism which is described in detail in the above mentioned Lasker patent. The upper or head section 4 contains the printing and accumulating mechanism, an early form 40 of which is disclosed and described in the patents to Powers, Nos. 1,245,502 and 1,245,504, modifications of which are shown in subsequent patents, all of which, as well as the commercial machine itself, are well known in the art and, therefore, do not constitute a part of this invention. 45

As most of the mechanism of the tabulator is described and disclosed in detail in the above mentioned patents, only those parts which are directly connected with the new device will be 50 described, using as nearly as possible the reference numerals used in the Lasker patent.

The only portion of the head section 4 which is pertinent to this invention is the drive shaft 5, and the adding or accumulating head operat- 55

ing arm 6 which is operatively connected to the drive shaft by a link 7 and arm 8 which rocks the arm 6 back and forth. The drive shaft 5 is driven by a motor in the base through the medium of a train of gears and shafting (not shown) disclosed and described in the above mentioned Lasker patent. The shaft 5 makes one revolution per cycle of the machine. Pivotaly mounted on the frame of the machine is an L-shaped arm 9, the vertical leg of which bears upon arm 6, and the lower or horizontal leg of which cooperates with a Bowden wire 10. The operation of this arm and wire will be explained hereinafter.

15 The principal members comprising the invention are disclosed in Figs. 2 and 3, and comprise a series of links and a ratchet counting member which are adapted to cooperate with the group control mechanism.

20 The group control mechanism is disclosed and described in detail in the above mentioned Lasker patent. Therefore, only the portions of the mechanism which are directly associated with the present device will be described, using the 25 same reference numerals as in the patent. As is well known in the art, the record retaining pins 158 (Fig. 8) are actuated by the sensing pins 174 passing through the perforations in a card. Each pin 158 has a spur 163 formed thereon which is adapted to cooperate with a cam slide 161 for locking the selected pin in the raised and operative position in order to retain the record for controlling the machine. Any other pin than those already operated will, upon being 30 raised, cause the shifting of the cam slide and the release of the formerly operated pin or pins.

In a machine having the group control mechanism a second cam slide 321 is provided which is associated with a spur 322 on each of the record 40 retaining pins. Upon a change of designation or the beginning of a new group of cards the newly selected pin will operate the second cam slide and oscillate a shaft 336 through the medium of an interponent 335 and a bail comprising 45 bar 338 and arms 337 secured to shaft 336. As the remainder of this mechanism is well known in the art and does not constitute a part of the new device, no further description will be given.

This shaft 336 is shown in Fig. 3 and has secured thereto an arm 352 which is rotated counterclockwise to release an arm 346 which causes the control mechanism to prepare the machine for automatically taking a total.

As an example of change of designation, if the 55 tabulator is itemizing the number of cans of grade "A" peaches which are contained in a certain group of cards and the end of the group of grade "A" cans is reached, the first card containing information relative to items of a different character will cause the camming slide to operate and start the group control mechanism, thereby causing the machine to space, take a total and space, and then proceed with the accumulation of data from the new group of cards.

60 Whereas, the group control mechanism is adapted to take totals automatically, it is proposed to use this mechanism for insuring that cards containing different interrelated data, such as a name and address, will follow each other. 70 The present invention is designed to check on name and address cards used in billing. The name, address and item cards all contain a similar number, for instance, the account number. This number will be the same until a new account 75 starts, at which time a change of designation

occurs. If the address card following the name card does not contain the correct account number, the group control mechanism operates and stops the machine. If, however, the name and address card both contain the same account number, the new device will no longer control the machine which will function in the normal manner. The group control mechanism will carry out its normal function of controlling the taking of a total upon change of data in the item cards. 10

The main drive of the machine is from a motor, not shown, located in the base 2, which is connected to the main drive shaft 25 through a clutch, one member of which is indicated at 33 (Fig. 1). The clutch may be of any well known 15 form similar to that shown in Fig. 6 of the above mentioned Lasker patent. The clutch is controlled by an arm 36 which is secured to shaft 37. This shaft passes from one side of the machine to the other and has secured thereto an arm 45 20 which is connected to a vertical link 46, which has a lever 47 pivotally secured thereto in the mid or connecting section 3. The parts, as shown in Fig. 1, are in their operative position with the machine running. In order to stop the machine, link 46 is forced downward, rocking the arm 36 against the tension of the spring 35, thereby releasing the clutch. The clutch is locked inoperative by a latch member 48 which engages a lug 50 secured to the link 46, thereby holding it in 30 its down, or motor disconnecting, position, as shown in Fig. 4. The latch 48 is operated by a spring 51. To restart the machine, the button 90 (Fig. 4) is pushed in rotating arm 86 to which is pivotally secured a hook shaped arm 87. The end of arm 87 contacts the end of latch member 48, thereby forcing it in a counterclockwise direction out of engagement with lug 50 permitting arm 46 to rise, thereby restarting the machine. 35

It is desirable that the machine always be 40 stopped in the same position, namely, that is when the card picker is in its extreme retracted reach position to feed a card into the machine. To this end the machine is not released directly by the operation of link 46, but is released by a 45 circular cam 52 (Fig. 4) mounted on the drive shaft 25, and having a projection 53 which operates a follower roller 54 and lever 55 which is pivoted at one end to the frame, and at the other end to link 57 which extends upward into the 50 connecting section 3.

For purposes of adjustment the lever which operates the link 46 is made in two pieces both pivoted at 60, one of which, 47, is pivotally connected to link 46. The other portion 61 has an 55 ear 62 bent over lever 47, and an adjusting screw bearing on the upper surface of lever 47, the two portions being held in operative relation by a connecting spring 64. At its end the lever 61 has a lug 65 adapted to be engaged by the end of a 60 link 66 which is pivoted to stop arm 68 which is, in turn, pivoted on rock shaft 70. The link 66 rests on the upper end of a push link 57 which rises each cycle of the machine. The link is normally positioned as shown in Fig. 4 with its nose forward of the lug 65. As long as link 66 remains in this position, the machine operation is uninterrupted. If by any means the lever 68 is swung in a clockwise direction bringing the nose of the link 66 under lug 65, the raising of lever 70 75 by the cam 52 rocks lever 61, 47 depressing link 46 and disengaging the clutch through arm 45 and shaft 37. It is obvious, therefore, that if the arm 68 is rotated by any control mechanism, that the machine will be stopped. 78

A device in accordance with the invention is provided for rotating arm 68. This device comprises a base member 31 on which is secured a vertical plate 11 (Fig. 5) on which is slidably mounted a control plate 12 having a cam face 14 formed on one edge, and teeth 15 cut in the opposite edge thereof. The teeth 15 on the plate 12 constitute a mechanism which is adapted to keep count of a predetermined number of cards 10 passing through the machine. Mounted on plate 11 is a feed pawl 16 (Figs. 2 and 6) having a pin 17 passing through a slot 18 in the plate 11, and secured to a sliding plate 19 on the rear of plate 11. The plate 19 is slidably secured to plate 11 by screw 20 which passes through a slot in plate 19, and is secured in plate 11. Feed pawl 16 is provided with a pin 21 which is used for disabling the feed pawl as will be hereinafter described. A spring 21A (see also Fig. 5), extended between pin 21 and a bracket on base plate 31, urges pawl 16 clockwise into engagement with teeth 15.

Slidably secured by a screw and slot connection to the plate 11 is a check pawl 22 (Fig. 2) which is spring-urged into engagement with the teeth 15 on control plate 12. The check pawl has a disabling pin 23 similar to pin 21 referred to above.

Pivotedly secured to the end of a shaft in the machine is an L-shaped arm 24 (Fig. 1), the lower end of which is adapted to cooperate with pin 17 on the feed pawl. The upper end of the arm is provided with a bearing plate 26 with which the end of Bowden wire 10 cooperates. The Bowden wire is rigidly clamped to plate 11 by a screw clamp member 27.

Pivotedly secured to plate 11 is an arm 28 which is connected to a parallel arm 29 by a bail member 30. The arm 29 (Fig. 3) is pivotedly mounted 40 on base plate 31 in front of and in horizontal alignment with arm 28.

Mounted on base plate 31, and in front of vertical plate 11 is a second vertical plate 32 (Fig. 2). Slidably secured by a screw and slot connection 45 to plate 32 is a holding member 38 formed as shown with a lip 39. Member 38 is held in its lowermost position by a spring 40. Pivotedly secured to plate 32 is a stop arm 41 which is held in engagement with member 38 by a spring 42.

50 Mounted on the base plate 31 is a rocking frame comprising a pair of parallel arms 43 which are secured together in rigid relation by a pair of shafts 34 and 44 (Fig. 3). Secured to the shaft 34 is an arm 67 (Figs. 2 and 3), the extreme end of 55 which is connected to arm 29 by a link 56. Also secured to shaft 34 is a latch plate 69 which is so designed as to cooperate with lip 39 of plate 38 when the frame 43 is held in its normal position by spring 58 as shown in Fig. 2. In this position 60 the roller or collar 59 (Figs. 3 and 5) on shaft 34 bears against the edge of cam plate 12 in a position to be operated upon by cam face 14 when the plate is raised.

Pivotedly mounted on base plate 31 is an L-shaped operating arm 72, the lower leg of which is connected to the center of arm 67 by a link 73. The upper end of arm 72 is connected to a solenoid 74 by a connecting rod 75 (Fig. 7).

Secured to the base 31 is a U-shaped frame 70 member carrying a shaft 76. Secured to shaft 76 is an arm 77 which is connected to the end of stop arm 41 by a link 78 (Fig. 2). Also secured to shaft 76 is an arm 79 positioned at 180° from arm 77, which is connected to a restoring button 81 75 by a rod 80. Secured to the rear end of shaft 76

(Figs 2 and 3) is an arm 82 having a pin 83 secured therein adapted to contact the arm 68 secured to the shaft 70 (Figs. 2 and 4).

When the shaft 5 (Fig. 1) is rotated by the main drive shaft on each sensing cycle of the machine 5 the arm 8 causes rocking arm 6 to move toward the front of the machine rocking L-shaped arm 9, which in turn pushes the Bowden wire 10 rotating arm 24 (Fig. 5) counterclockwise. The horizontal leg of arm 24 cooperates with pin 17 10 to raise the lifting pawl 16, thereby raising the control plate 12 which is held in its raised position by check pawl 22.

The first card sensed causes certain record retaining pins 158 to be set up and the data is accumulated and printed in the machine. At the same time the arm 24 has been operated causing feed pawl 16 to raise the cam plate 12 one step. This operation takes place after the cam slide in the group control mechanism has been 29 positioned.

If the next card sensed is one in which the interrelated data changes, the cam slide 321 will cause the group control mechanism to oscillate rocking arm 352 (Fig. 7) in a counter-clockwise 25 direction, closing contacts 85, which, in turn, close a circuit for energizing solenoid 74. The operation of solenoid 74 through the rod 75 moves arm 72 in a clockwise direction, thereby raising the arm 67 through the medium of arm 73 30 (Fig. 2).

The raising of arm 67 (Fig. 2) also raises latch plate 69 which, in turn, raises the latch member 38, until stop arm 41 is free to be rotated in a clockwise direction by the spring 42 (Fig. 2). 35 Since arm 41 is connected to arm 77 by link 78, the clockwise rotation is transmitted to shaft 76. The rotation of shaft 76 raises arm 82 which, in turn, rotates arm 68 through the medium of pin 83. The clockwise rotation of arm 68 (Fig. 4) 40 inserts the nose of arm 66 under lug 65, thereby causing the machine to stop as described above (Fig. 4).

The elevation of arm 67 (Fig. 2) also caused the rotation of arms 28 and 29 in a counter- 45 clockwise direction due to the fact that arm 29 is connected to arm 67 by link 56. The bail 30 connected between arms 28 and 29 is moved to the left in Figs. 3 and 5, thereby contacting pins 21 and 23 withdrawing the stop pawl 22 and stepping pawl 16 from teeth 15, thus releasing cam plate 12 and permitting it to be restored to normal by spring 49.

Plate 38 is restored to normal by depressing button 81 which rotates shaft 76 in a counter-clockwise direction through rod 80 and arm 79. The rotation of shaft 76 rotates arm 77 drawing link 78 to the right and thereby rotating stop 41 in a counter-clockwise direction. The cooperating sloping faces of stop 41 and plate 38 cause the plate to be raised until the edge of the stop is free when the plate 38 is drawn down by spring 40 to its normal position (Fig. 2). The raising of plate 38 also permits the plate 69 to drop under the edge of lip 39 and so restore to normal. 65

If the second card sensed is one on which the interrelated data remains the same, the slide 12 (Fig. 5) will be raised, as described above, until the cam 14 contacts collar 59 thereby rotating frame 43 in a clockwise direction withdrawing 70 latch plate 69 from under the lip 39 so that arm 72 no longer controls the stopping of the machine.

A third card causes the stepping latch to raise the plate 12 to its highest position as shown in Fig. 5. If no change of designation takes place 75

the pawl 16 will continue to step, but the plate 12 will not be raised due to its lower portion being cut away.

When a change of designation occurs after three or more cards have been sensed, the arm 352 rotates closing contacts 85 which closes the operating circuit for magnet 74. The operation of magnet 74 rotates arm 67 as described above. This does not, however, stop the machine, but only restores the plate 12 to normal. This is due to the fact that lug 69 has been cammed out of contact with lip 39. Therefore, the plate 38 will not be raised and the machine is not stopped, but the pawls 16 and 22 are withdrawn and plate 12 is restored to normal.

Sufficient clearance is provided between the lip 39 and the latch plate 69 to permit these parts to restore to normal, when the slide 12 is lowered, without disturbing the plate 38.

It is obvious that plate 12 may be provided with any number of combinations of teeth 15 and cams 14 to stop the machine unless a predetermined number of cards containing related data follow one another.

While I have described what I consider to be a highly desirable embodiment of my invention, it is obvious that many changes in form could be made without departing from the spirit of my invention, and I, therefore, do not limit myself to the exact form herein shown and described, nor to anything less than the whole of my invention as hereinbefore set forth, and as herein-after claimed.

What I claim as new, and desire to secure by Letters Patent, is:

1. In a perforated card-controlled machine, the combination of a group control mechanism having an oscillating arm therein, a drive mechanism for said machine, an electro-magnet controlled by said oscillating arm, a rocking frame having a shaft therein, a latch plate having a lip thereon adapted to cooperate with a lug secured to said shaft, a lever secured to said shaft, an L-shaped arm connected to the armature of said electro-magnet, means normally restrained by said latch plate for disabling said drive mechanism, and a link connecting said L-shaped arm to said lever whereby the operation of said armature raises said latch plate to release said disabling means.

2. In a machine controlled by groups of cards containing diversified inter-related data perforations, a drive mechanism under control of a clutch, a group control mechanism having an oscillatable arm, and means for oscillating said arm on data changes therein, a counting mechanism operated by the machine on each cycle thereof, an electro-magnet controlled by said oscillating arm, a latch mechanism comprising a latch plate having a lip formed thereon, a rocking frame having a shaft therein, said shaft having a lug and a lever secured thereto, said lug adapted to cooperate with said lip to raise said latch plate, an L-shaped arm connected to the armature of said electro-magnet, a link connecting said L-shaped arm to said lever whereby the operation of said electro-magnet raises said latch plate to release means for actuating said clutch to disable said drive mechanism should said data change before a predetermined number of cycles have been made, and means in said counting mechanism for moving said rocking frame to prevent the cooperation of said lip and said lug should the data fail to change before a predetermined number of cycles have been made.

3. In a record controlled machine, the combination of a machine drive mechanism under control of a clutch, a group control mechanism having an oscillatable arm and means for oscillating the arm on data changes in said records, an electro-magnet operable under control of said oscillating arm, a latch mechanism operable to effect the disengagement of said clutch comprising a latch plate having a lip formed thereon, a rocking frame having a shaft therein, said shaft having a lug and a lever secured thereto, said lug being arranged to cooperate with said lip to raise said latch plate, an L-shaped arm connected to the armature of the electro-magnet, and means connecting the L-shaped arm to the lever whereby the operation of the electro-magnet raises the latch plate to disengage the clutch on data changes.

4. In a record controlled machine, the combination of a drive mechanism, a group control mechanism, means operable under control of the group control mechanism to disable the drive mechanism, a counting mechanism operated during each machine cycle, and means controlled by the counting mechanism to render the group control mechanism ineffective to control the disabling means after a predetermined number of cycles.

5. In a record controlled machine, the combination of a drive mechanism, means operable to effect the stopping of the drive mechanism, a group control mechanism operative on a change of designation in successive records to condition the stopping means for operation, a cyclically operated counting mechanism, and means controlled by the counting mechanism after a predetermined number of machine cycles to render the group control mechanism ineffective to condition the stopping means.

6. In a record controlled machine, the combination of a drive mechanism, means operative to effect the stopping of the drive mechanism, blocking means to hold said stopping means inoperative, a group control mechanism operative on a change of designation in successive records to disengage the blocking means from the stopping means, a cyclically operated counting mechanism, and means controlled by the counting mechanism after a predetermined number of machine cycles to render the group control mechanism ineffective to disengage the blocking means.

7. In a record controlled machine, the combination of a drive mechanism, means operable to effect the stopping of the drive mechanism, resilient means to cause the operation of the stopping means, blocking means to prevent the operation of the stopping means by the resilient means, a group control mechanism operative to disengage the blocking means from the stopping means on a change of designation in successive records, a cyclically operated counting mechanism, and means controlled by the counting mechanism to render the group control mechanism ineffective to disengage the blocking means.

8. In a record controlled machine including a group control mechanism and a stop arm arranged when operated to effect the stopping of the machine, the combination of resilient means to urge the stop arm to operated position, blocking means to prevent the operation of the stop arm, and means operated by the group control mechanism to render the blocking means ineffective.

9. In a record controlled machine, the combi-

nation of a drive mechanism, means operable to effect the stopping of the drive mechanism, a group control mechanism operative on a change of designation in successive records to condition the stopping means for operation, a machine cycle counting mechanism including a cam surface movable through successive steps in successive machine cycles, and means controlled by said cam surface after a predetermined number of machine cycles to render the group control mechanism ineffective to condition the stopping means.

10. In a record controlled machine, the combi-

nation of a drive mechanism, means operable to effect the stopping of the drive mechanism, a group control mechanism operative on a change of designation in successive records to condition the stopping means for operation, a counting mechanism including a cam surface and an actuating pawl to move said cam surface through successive steps in successive machine cycles, and means controlled by the cam surface after a predetermined number of cycles to render the group control mechanism ineffective to condition the stopping means. 5 10

EDWARD ROWLAND MYERS.
